US00D841635S

(12) **United States Design Patent** (10) **Patent No.:** **US D841,635 S**
(45) **Date of Patent:** **** Feb. 26, 2019**

(54) **MOBILE PHONE**

(71) Applicant: **Toughbuilt Industries, Inc.**, Glendale, CA (US)

(72) Inventors: **Michael H. Panosian**, Irvine, CA (US); **Joshua Keeler**, Bradbury, CA (US)

(73) Assignee: **TOUGHBUILT INDUSTRIES, INC.**, Lake Forest, CA (US)

(**) Term: **15 Years**

(21) Appl. No.: **29/601,793**

(22) Filed: **Apr. 26, 2017**

CLAIM

The ornamental design for a mobile phone, as shown and described.

DESCRIPTION

FIG. 1 is a front perspective view of a mobile phone showing our new design;

FIG. 2 is a rear perspective view of the mobile phone illustrated in FIG. 1;

FIG. 3 is a front elevation view of the mobile phone illustrated in FIG. 1;

FIG. 4 is a back elevation view of the mobile phone illustrated in FIG. 1;

FIG. 5 is a left side elevation view of the mobile phone illustrated in FIG. 1;

FIG. 6 is a right side elevation view of the mobile phone illustrated in FIG. 1;

FIG. 7 is a top side elevation view of the mobile phone illustrated in FIG. 1; and,

FIG. 8 is a bottom side elevation view of the mobile phone illustrated in FIG. 1.

The broken lines are included for the purpose of illustrating environmental subject matter and form no part of the claimed design.

1 Claim, 6 Drawing Sheets
